UNITED STATES PATENT OFFICE.

FRED M. L. SCHNEIDER, OF SYLVAN GROVE, KANSAS.

GAME.

1,182,802.

Specification of Letters Patent.

Patented May 9, 1916.

Application filed November 20, 1915. Serial No. 62,591.

To all whom it may concern:

Be it known that I, FRED M. L. SCHNEIDER, a citizen of the United States, residing at Sylvan Grove, in the county of Lincoln and 5 State of Kansas, have invented new and useful Improvements in Games, of which the following is a specification.

This invention contemplates the provision of a game, embodying a game board divided 10 into two sections, each having a goal representing a "capital", and images indicative of soldiers adapted to be moved by the players along certain lines or courses, with the object of each player being to seize the 15 "capital" of the other, under certain conditions hereinafter more fully described which renders the game exceedingly interesting and amusing.

The nature of the invention will be better 20 understood from the following description when taken in connection with the accompanying drawing wherein like numerals of reference indicate similar parts in the several views and in which:—

25 Figure 1 is a perspective view of the playing surface of the board showing the initial arrangement of the game pieces thereon. Fig. 2 is a similar view showing the initial arrangement of the game pieces for three 30 players. Fig. 3 is a view similar to Fig. 1 showing some of the moves of the game. Fig. 4 is a similar view showing the arrangement of the game pieces for four players.

35 The proposed game consists of a board constructed from any suitable material of desired dimensions, and divided into two sections 5 and 6 respectively. The playing surface of the board is ruled off by oppositely extending diagonal lines 7 in a manner similar to the well known form of checker board, excepting the lines 7 are double to distinguish these lines from the lines 8 disposed between the pairs of lines 40 7 in parallelism therewith, or the lines 7 may be heavier and of a distinctive color than the lines 8 to render these lines readily distinguishable to the players. Each section 45 of the board is provided with a character representing a "capital", and as shown in this instance the character is in the nature of a ring 9 encircling the point of inter-

section of two of the lines 7 adjacent one end of the board, while the board is marked off with the squares 10 at the four points of 55 intersection of the lines 8 at diametrically opposite points about the "capital".

With a board of this character I employ two sets of game pieces, each set including a plurality of relatively small images indicated at 11, and a number of relatively large images indicated at 12. The images of one set are of a distinctive color from those of the other set, while all the images are indicative of soldiers. The smaller images 60 are initially placed upon the points of intersection of the lines 7 that surround the "capital", and are to be hereinafter known as "guards", while the relatively large images are to be initially placed upon the 65 squares 10, and are the principal characters that do the fighting with a view of preventing the opposition from seizing the "capital" in the manner to be presently described. Each set of game pieces also includes an additional image indicated at 13 70 to be known as the red cross figure, which figure is also indicative of a soldier, and is initially placed upon the division line 15 between the sections 5 and 6 at a point adjacent the sides of the board. The red cross figures 13 may be distinguished from each other, and also from the remaining game pieces in any suitable manner such as by 75 size or configuration, but as shown in this 80 instance they are distinguished by color.

The game is played somewhat similar to the game of checkers, each player being entitled to one move at a time, and the move being limited from one cross line to the 90 other. The images 11 can be moved forward only, and their duty is to block the moves of images of the other player toward the "capital". The images 11 can take the place of any of the images 11 of the opposition when the opportunity presents itself, that is by "jumping" the image as in the 95 game of checkers. The image thus "jumped" is immediately removed from the board out of play.

100 The relatively large images 12 can be moved along any of the lines, either backward or forward as far as the lines are clear. They also can take the place of any other

image belonging to the opposition, by "jumping" as hereinabove described. The red cross figures 13 can also be moved backward or forward as the images 12, but can-
5 not be "jumped", nor can they take the place of other images by "jumping" the latter, and consequently these red cross figures can-
not be removed from the board by other im-
ages, but can block the moves of such im-
10 ages. The player who first succeeds in plac-
ing his red cross figure in the "capital" of the other player as shown in Fig. 3 wins the game.

The arrangement of the game pieces here-
15 inabove described permits of but two players playing the game, but in order that three players may play I employ three red cross figures and initially arrange the same in the manner shown in Fig. 2, one upon the di-
20 vision line 15 between the sections 5 and 6 of the board, and the remaining two at the opposite sides of the division line adjacent one side of the board. Two of the players play with the images arranged upon the
25 respective sections 5 and 6 moving in the same manner hereinabove described. It is to be understood however that neither of the two players mentioned have a red cross figure, the three red cross figures belonging
30 to the third player.

When the game is played by three players it is scored by points, the relatively small images counting one point, while the larger images each have a value of five. Conse-
35 quently it is the object of the players to capture during the play of the game as many of the images of the opposing players as possible, before the third player succeeds in placing one of his red cross figures in the "capital" of either of the other two players. The first two mentioned players capture the images of the opposition by "jumping" the images as in the game of checkers, while the third player captures the images of the
40 opposition by catching one of the images between two of his red cross figures as indicated at α in Fig. 3. When the third player succeeds in placing one of his red cross figures in the "capital" of either of the two
45 players he is entitled to all the images of both players which are left upon the board. The points are then scored. There should be three games played, and the one having the highest total for the three games wins. By
50 playing three games each of the players is entitled to play one game with the red cross figures.

When the game is to be played by four players, two of the four players play with
60 two of the red cross figures, which are pro-
vided with some characteristic to distinguish the two sets of red cross players. The game is played somewhat similar to that herein-
above described with three players, each
65 player being entitled to one move at a time,

with the two players in possession of the red cross figures trying to place one of his figures in either of the two "capitals." In addition to this fact the red cross figures of one player can capture the red cross figures 70 of the other player, and also be captured by said red cross figures of the other player and removed from the board, while the remaining two players score their points by "jumping" each other's images as in the game of 75 checkers. The player who first succeeds in placing one of his red cross figures in either of the two "capitals" is entitled to all the images remaining on the board. The points of the game are then scored, with the rela- 80 tively small images having a value of one and the relatively large images having the value of five points. Four games should be played, thus giving each of the players an opportunity to play with the red cross fig- 85 ures, and the one scoring the highest total of points for the four games wins. When playing partners the two players playing with the red cross figures are partners, in which instance they try to capture any of 90 the other images, this being accomplished by catching an image in between two of the red cross figures as clearly shown at α in Fig. 3. The object however still remains in the game of partners to place one of the red 95 cross figures in either of the two "capitals," at which time the players playing with the red cross figures are entitled to all of the images still remaining upon the board. When playing partners two games instead 100 of four are to be played, which gives each side an opportunity to play with the red cross figures, and the side obtaining the highest total of points for the two games wins. 105

In Fig. 4 I have shown substantially the same arrangement of the game pieces as disclosed in Fig. 3, excepting that I make use of an additional game piece indicated at 16 which may be distinguished from the remaining game pieces either by shape or color. With these additional game pieces included, two, three or four players may play the game. The game pieces 16 can be moved on all lines from one point of in-
110 tersection to the other, either backward or forward, and can take the place of other images by "jumping" the latter as in the game of checkers, except the red cross figures. When two play the game with the game pieces 16, the two players will have two red cross figures each to play with. The red cross figures are primarily used to block the moves of other images, and are also capable of capturing the other images in the 115 manner hereinabove described, the game being won by the player who first succeeds in placing one of his red cross figures in the "capital" of the other player. 120

It is believed that from the foregoing de- 130

scription the nature and advantages of the invention will be thoroughly understood without requiring a more extended explanation and therefore the same has been 5 omitted.

What is claimed is:—

1. A game comprising a playing surface marked off by diagonally disposed intersecting lines, and having a division line defining 10 playing sections, each section being provided with a character representing a "capital," and a plurality of distinguishing characters surrounding said "capital," and a plurality of game pieces divided into sets, the game 15 pieces of the respective sets being adapted to be moved along certain of said lines, and

said sets being distinguishable from each other.

2. A game comprising a playing surface marked off by intersecting lines, a goal adjacent each end of the surface, a plurality of sets of game pieces, the game pieces of certain of said sets having fixed relatively high and low values, and the game pieces of another set having like values but values different from those of the other sets. 20 25

In testimony whereof I affix my signature in presence of two witnesses.

FRED M. L. SCHNEIDER.
